MACHINE FOR DYEING TEXTILE FABRICS

Alexander J. Belokopytoff, New York, N. Y., assignor to Paul N. Robins, Scarsdale, N. Y.

Application October 18, 1941, Serial No. 415,537

5 Claims. (Cl. 91—9)

My invention relates to textile printing machines and has particular reference to machines for continuous printing of various designs on rolls of textile fabrics.

My invention has for its object to provide a machine for automatically forming various designs on a printing matrix, and for continuously transferring these designs on a bolt of a textile fabric.

According to my invention, the design is prepared by placing particles of variously colored dyes on a layer of a gelatinous solution and, if desired, further spreading or raking the dyes so as to obtain desired patterns. The fabric is then placed on the gelatinous layer, the design being thus transferred to the fabric. In order to make the process continuous, the matrix is formed at one end of an endless belt, the dyes are then applied to the matrix, the matrix with the dyes manipulated as by raking or combing, and a fabric is applied to the colored layer from a roll placed above the belt. The belt and the fabric are moved at the same speed, the printed fabric being then dried while the belt is being cleaned and washed to make it ready for a new application of the matrix.

Another object of my invention is to provide means to deliver the dye solutions in measured quantities or drops of variable size and to distribute the drops in a desired pattern over the matrix.

Another object of my invention is to provide means to automatically rake or comb the matrix with the drops of the dyes for producing geometrically uniform patterns, such as spirals, zig-zags, figures 8, etc., their combinations or superpositions. By changing the diameters of the circles forming the pattern and combinations of the figures, in connection with the variety of differently spaced colors, it is possible to obtain a great variety of designs.

Another object of my invention is to independently adjust the rate of the dye drop formation and the rate of the raking or combing action, thereby changing the frequency of the drops and intervals between the drops in relation to the frequency of the figures.

Still another object of my invention is to provide means to remove the fabric from the belt and to dry the fabric.

My invention is more fully described in the accompanying specification and drawings, in which:

Fig. 1 is an elevational view of my machine;

Fig. 2 is a top plan view of the same;

Fig. 3 is a detail sectional view of a drop delivering and spreading mechanism;

Fig. 4 is a fractional plan view of the same;

Fig. 5 is a fractional detail view of a simplified device for delivering dye drops;

Fig. 6 is a fractional detail plan view of a raking mechanism for producing zig-zag pattern;

Fig. 7 is a side view of the same;

Fig. 8 is a detail plan view of a raking mechanism for producing figure 8 pattern;

Fig. 9 is a detail view of a device for forming gelatinous layer or matrix;

Fig. 10 is a view of a spiral formed with the device shown in Figs. 6 and 7;

Fig. 11 is a view of a zig-zag pattern formed with the device shown in Fig. 4;

Fig. 12 is a pattern in the form of figure 8 produced by the device shown in Figs. 8 and 9;

Fig. 13 is a detail view of eccentrics.

My textile printing machine consists of a frame having two upper angle irons or beams 1 supported on posts 2 and joined by angle irons or beams 3 at the top and beams 4 at the bottom. A table 5 (Fig. 9), preferably made of asbestos, pressed wood or plastic composition, is supported on the upper beams 3. The table forms a support for the upper portion of an endless belt 6 mounted on drums 7 and 8. The drums have shafts 9 and 10 journaled in bearings 11 and 12 supported on posts 2. A diagonal brace 13 at the rear and a cross beam 14 at the front further strengthen the frame. The belt is preferably made of a smooth, impervious-to-water material, such as rubber. A sprocket 15 is mounted on the shaft 9 and is connected by a chain 16 with a small sprocket 17 on the end of a shaft 18 of a speed reducer 19 driven by a motor 20.

A tank 24 is mounted on legs 25 on the frame members 1 above the belt and is provided with a plurality of tubes 26 terminating with spreading nozzles 27 supported immediately above the surface of the belt, as shown in detail in Fig. 9. Valves 28 are provided in the tubes 26 and can

be simultaneously closed or opened by a cross bar 29. The tank is filled with a suitable gelatinous solution, preferably the extract of Irish moss. The solution is prepared relatively thin, so that it can readily flow through the pipes 26, spreading out over the surface of the belt (Fig. 9). A rear board 30, touching the belt, prevents the solution from flowing back over the curved portion of the belt, a front board 31 being so adjusted in its elevation above the belt by screws

32 that a certain definite thickness of the ge-

latinous layer 33 is maintained on the moving belt.

A large number of small tanks 34 are supported on bars 35 and legs 25, every tank having a rubber pipe 36 extending to the belt and terminating with a nozzle 31 (Figs. 3 and 5), preferably made of a hard material such as hard rubber, glass, plastic composition, etc. Individual valves 38 are provided for every pipe 36. The pipes 36 are placed between the side of a bar 39 (Fig. 3) and a flat side of a rod 40 rotatively supported at its ends in suitable bearings and backed by a second bar 43. The flat side of the rod is so arranged that the rod, when turned, compresses the pipes by its edge 44, closing the pipes and stopping the flow of the dyes. The rod has arms 45 at the ends pivotally connected with plungers 46, the latter being periodically raised by eccentrics or cams 47, 47', 47'' on shafts 48, 49. Weights 21 are mounted on extensions 22 of the arms 45 keeping the arms turned downward and closing the pipes. Handles 23 may be used for manually opening the pipes. The cams 47, 47', 47'' are of the same diameter but have different peripheral length of their eccentric portions. By shifting the cam on the shaft 48 or 49, a selected cam may be placed in an operative position, so as to open the pipes for a shorter or longer period of time, depending on the length of the peripheral or eccentric portion of the cam.

The shafts 48 and 49 are connected together by a chain 50 on sprockets 51, 56 and are journaled in bearings 51. A sprocket 58 on the shaft 48 is connected by a chain 59 with a similar sprocket 60 on a driving shaft 61 journaled in bearings 62. The shaft 61 has a key 63 on which slides a friction pinion 64 engaging a friction disc 65 on a shaft 65', connected by a chain 52 and sprockets 53, 54 with the reducer 19. A shifting fork 61 is provided for changing the position of the pinion 64 on the disc thereby changing the gear ratio between the shafts, 48, 49 and 61, the fork being operated by a manually turnable screw 66.

The nozzles 31 are placed in a supporting bar 68 having suitably spaced holes, as shown in Figs. 3 and 4, the end of the bar having a plate 69 with a transverse slot 70 engaging a pin 71 fitted in one of the holes 13, 14 of a disc 15 mounted on a shaft 16 journaled in a bearing 12 and rotated by the shaft 48 through bevel gears 71. Rollers 78 guide the bar 68 in its reciprocating movement across the belt with the matrix, for delivering the dye drops in a zig-zag pattern. The amplitude of the zig-zags can be varied by placing the pin 71 in one or the other of the holes 13, 14, the holes being located at different distances from the axis of rotation of the disc.

Another arrangement for supporting the nozzles 31 is shown in Fig. 5. The bar 55 has U-shaped clamps 79 at the ends slidably fitted on the edges of the beams 1 and provided with set screws 80 for tightening the clamps in a desired position.

The drops can be also spread over the belt in a spiral-shaped pattern if the ends of bar 68 are pivoted to the pins 71 extending from the discs 15, similarly to the arrangement shown in Figs. 6 and 7, which illustrate the mechanism for operating matrix combing rakes or combs. The rakes consist of bars 81 with pins 82 extending to the surface of the belt and passing through the thickness of the matrix. The ends 81' of the bars are pivoted to pins 84 extending from discs 85 mounted on shafts 86 journaled in bearings

87 and rotated by a shaft 83 through bevel gears 88. The discs 85 are also provided with several holes 89, 89' for the pins 84 located at different distances from the center for adjusting the size of the spirals 90 (Fig. 10) described by the points of the pins 82.

A mechanism for drawing zig-zag shaped lines 91, Fig. 11, is shown in Figs. 1 and 2, being similar to the device for operating the nozzles 31 and shown in Fig. 4. The end of a raking bar 92 has a slotted plate 93 engaging a pin 71' on a disc 84 and is rotated by the shaft 83 through bevel gears 88.

Fig. 8 illustrates in detail a mechanism for drawing double spirals in the form of figure 8 96, Fig. 12. The raking bar 97 has plates 98 at the ends with slots 99 for eccentrics 100 mounted on shafts 101 journaled in bearings 102 and rotated by the shaft 83 through bevel gears 88. The plates 98 have also transverse slots 105 for eccentrics 106 on the shafts 107 journaled in bearings 108 and rotated by the shaft 83 through bevel gears 109. The latter are so arranged that the eccentric 106 makes two revolutions for one revolution of the eccentric 100, thereby oscillating the bar sidewise twice during one revolution of the main eccentric 100 and thereby producing double spirals in the shape of figure 8.

The shaft 83 is connected by a chain 110 and sprockets 111, 112 with a similar shaft 113 at the other side of the machine, the latter shaft being connected by a chain 114 and sprockets 115, 116 with a second driving shaft 117 with a sliding friction pinion 118 engaged by a friction disc 119 mounted on the other end of the shaft 65'. A shifting fork 126 similar to the fork 67 is provided for the pinion 118.

With the independent adjustment of the rotational velocity of the shafts 48, 49 and 83, 113, it is possible to vary the rate at which the dye drops are placed on the matrix in relation to the speed of movement of the latter and to the spacing of the spiral loops by the rakes. A large variety of patterns can be therefore obtained by using various combinations of speeds, colors, etc.

A roll 129 of fabric or cloth 130 is removably supported in bearings 131 at the top of posts 132 mounted on the beams 1 near the last rake mechanism. The fabric or cloth is passed over straightening rolls 133 which remove wrinkles from the cloth, the latter being then placed on the matrix by a V-shaped spreading bar 134 adjustably supported on the beams 1.

The cloth, upon leaving the belt, passes into a drier chamber consisting of an upper hood 135, shown in Fig. 1 with the side cover removed, and lower hood 136, and having a plurality of rolls 137 on shafts 138 journaled in bearings 139. Hot air is delivered into the drier by a fan 140, blowing the air through a steam heater 141 or other similar air heating device, the air passing through the lower hood and through the cloth into the upper hood from which the cooled moist air escapes through a duct 142.

The cloth is pulled through the drier at the same speed at which the belt is moved by the drums, the pulling being effected by rolls 143, 144 rotated by the rear drum 8 through a belt 145 and pulleys 146, 147, the pulley 146 consisting of two tapering portions which can be moved toward each other by a nut 148 on a screw 149 for finely adjusting the speed of the drawing rolls 143, 144. The shafts of the rolls are supported in bearings 150, 151, the upper bearings being under pressure of springs 152.

A scraper 153 is provided for removing particles of the matrix 33 from the cloth 130 prior to its entering the drier. A sprayer pipe 154 is used for washing the scraper. A similar scraper 155 is provided for removing the used matrix from the belt 6, a sprayer pipe 156 delivering water for washing the scraper and the belt. The latter may be further cleaned by rotary brushes 157 operated by the driving shaft 81 through gears 151, with spray pipes 158 at the sides of the brushes. A drip pan 159 collects the dirt from the belt.

It is understood that my textile printing machine may be further modified without departing from the spirit of the invention, as set forth in the appended claims.

I claim as my invention:

1. A machine for dyeing textile fabrics, comprising an endless belt, rollers movably supporting the belt, means to apply a layer of gelatinous solution to the belt, means to deposit drops of coloring solutions to the layer, a plurality of rakes with pins adapted to touch the layer, means to oscillate the rakes with the pins, thereby spreading the drops into fancy patterns, means to adjust the amplitude of the oscillations, means to apply a fabric to the layer on the belt, thereby transferring the patterns onto the fabric, a plurality of rollers supporting the fabric beyond the belt, means to rotate the rollers, thereby moving the belt and the fabric at the same speed, and means to remove the used layer from the belt.

2. A machine for dyeing textile fabrics, comprising an endless belt, rollers movably supporting the belt, means to apply a layer of gelatinous solution to the belt, means to deposit drops of coloring solutions to the layer, rakes adapted to touch the layer, means to impart a rotary motion to the rakes, thereby spreading the coloring drops into fancy patterns, means to adjust the radius of rotation of the rakes, means to regulate the speed of rotation of the rakes, means to apply a fabric to the layer, thereby transferring the patterns to the fabric, a plurality of rollers supporting the fabric beyond the belt, means to remove the used layer from the fabric upon its separation from the fabric, means to clean the fabric, and means to rotate the rollers, thereby moving the belt and the fabric at substantially the same speed.

3. A machine for dyeing textile fabrics, comprising an endless belt, rollers movably supporting the belt, means to apply a layer of gelatinous solution to the belt, a plurality of wells for coloring dyes supported above the belt, flexible pipes extending from the wells to the layer, means to support the ends of the pipes at spaced intervals from each other, a stationary bar extending along the pipes at one side, a rotary rod extending along the pipes at the other side having a flat side for releasing the pipes, means to rotate the rod for periodically clamping the pipe and stopping the flow of the dyes to the layer, means to apply a fabric to the layer with the dyes, thereby transferring the dyes to the fabric, means to rotate the rollers for moving the belt with the fabric, and means to remove the dyed fabric from the belt.

4. A machine for dyeing textile fabrics, comprising an endless belt, rollers movably supporting the belt, means to apply a layer of gelatinous solution to the belt, a plurality of wells for coloring dyes supported above the belt, flexible pipes extending from the wells to the layer, means to support the ends of the pipes at spaced intervals from each other, a stationary bar extending along the pipes at one side, a rotary rod extending along the pipes at the other side having a flat side for releasing the pipes, means to rotate the rod for periodically clamping the pipe and stopping the flow of the dyes to the layer, means to regulate the amount of dye solutions delivered during one cycle of movement of the rod, means to apply a fabric to the layer with the dyes, thereby transferring the dyes to the fabric, means to rotate the rollers for moving the belt with the fabric, and means to remove the dyed fabric from the belt.

5. A machine for dyeing textile fabrics, comprising a table, a member movably supported on the table, means to form a layer of gelatinous composition on the member, a scraper bar supported at an elevation above the belt to regulate the thickness of the layer, means to apply measured quantities of dye solutions to the layer, means to apply a fabric to the layer for transferring the dye solutions thereto, means to move the member with the fabric, and means to remove the fabric from the member.

ALEXANDER J. BELOKOPYTOFF.
